(57) **CLAIM**

The ornamental design for a vision apparatus comprising frame and pivotable display as shown and described.

DESCRIPTION

FIG. 1 is an upper front perspective view of the vision apparatus comprising frame and pivotable display with the pivotable display down;

FIG. 2 is an upper rear perspective view of the vision apparatus of FIG. 1 comprising frame and pivotable display with the pivotable display down;

FIG. 3 is an upper front perspective view of the vision apparatus of FIG. 1 comprising frame and pivotable display with the pivotable display down and removable battery removed;

FIG. 4 is an upper rear perspective view of the vision apparatus of FIG. 1 comprising frame and pivotable display with the pivotable display down and removable battery removed;

FIG. 5 is a front view of the vision apparatus of FIG. 1 comprising frame and pivotable display with the pivotable display down;

FIG. 6 is a rear view of the vision apparatus of FIG. 1 comprising frame and pivotable display with the pivotable display down;

FIG. 7 is a right side view of the vision apparatus of FIG. 1 comprising frame and pivotable display with the pivotable display down

FIG. 8 is a left side view of the vision apparatus of FIG. 1 comprising frame and pivotable display with the pivotable display down

FIG. 9 is a top view of the vision apparatus of FIG. 1 comprising frame and pivotable display with the pivotable display down;

FIG. 10 is a bottom view of the vision apparatus of FIG. 1 comprising frame and pivotable display with the pivotable display down;

FIG. 11 is an upper front perspective view of the vision apparatus comprising frame and pivotable display with the pivotable display up;

FIG. 12 is an upper rear perspective view of the vision apparatus of FIG. 11 comprising frame and pivotable display with the pivotable display up;

FIG. 13 is an upper front perspective view of the vision apparatus of FIG. 11 comprising frame and pivotable display with the pivotable display up and removable battery removed;

FIG. 14 is an upper rear perspective view of the vision apparatus of FIG. 11 comprising frame and pivotable display with the pivotable display up and removable battery removed;

(Continued)

FIG. 15 is a front view of the vision apparatus of FIG. 11 comprising frame and pivotable display with the pivotable display up;

FIG. 16 is a rear view of the vision apparatus of FIG. 11 comprising frame and pivotable display with the pivotable display up;

FIG. 17 is a right side view of the vision apparatus of FIG. 11 comprising frame and pivotable display with the pivotable display up

FIG. 18 is a left side view of the vision apparatus of FIG. 11 comprising frame and pivotable display with the pivotable display up

FIG. 19 is a top view of the vision apparatus of FIG. 11 comprising frame and pivotable display with the pivotable display up; and,

FIG. 20 is a bottom view of the vision apparatus of FIG. 11 comprising frame and pivotable display with the pivotable display up.
